COMBINED LAMP AND PICTURE HOLDER

Kenneth Roger Morehead, 205 Adams Ave.,
Cuyahoga Falls, Ohio 43221

Filed Jan. 3, 1969, Ser. No. 15,205

Term of patent 14 years

Int. Cl. D26—02

U.S. Cl. D48—20

Fig. 1

Fig. 2

FIG. 1 is a top plan view of the combined lamp and picture holder;

FIG. 2 is a front elevational view thereof, the rear being a mirror image of the front except for the omission of the switch and the addition of a hole for the AC cord;

FIG. 3 is a side elevational view thereof, the opposite side being a mirror image of the side shown in the drawing.

I claim:

The ornamental design for a combined lamp and picture holder, as shown and described.
